(57) **CLAIM**

The ornamental design for a stud finder, as shown and described.

DESCRIPTION

The product of this design is used for detecting the structural components in walls or the buried objects, such as the studs, steel bars or electrical wires, etc.

FIG. 1 is a front elevational view of the design;
FIG. 2 is a back elevational view of the stud finder in FIG. 1;

FIG. 3 is a top plan view of the stud finder in FIG. 1;
FIG. 4 is a bottom plan view of the stud finder in FIG. 1;
FIG. 5 is a right side elevational view of the stud finder in FIG. 1;

FIG. 6 is a left side elevational view of the stud finder in FIG. 1; and,
FIG. 7 is a perspective view of the stud finder of FIG. 1.
